UNITED STATES PATENT OFFICE.

WILLIAM E. MILLER, OF GOBLEVILLE, MICHIGAN.

SEALING-MACHINE.

1,299,499.

Specification of Letters Patent.

Patented Apr. 8, 1919.

Application filed July 11, 1918. Serial No. 244,349.

To all whom it may concern:

Be it known that I, WILLIAM E. MILLER, a citizen of the United States, residing at Gobleville, county of Van Buren, State of Michigan, have invented certain new and useful Improvements in Sealing-Machines, of which the following is a specification.

This invention relates to improvements in sealing machines.

10 My improved sealing machine is especially designed by me for sealing the waxed paper wrapping of sandwiches and the like, although desirable for use in other relations.

The main objects of this invention are:

15 First, to provide a machine for sealing waxed wrappers upon sandwiches and like articles of more or less delicate nature.

Second, to provide in a sealing machine an improved wrapping means.

20 Third, to provide an improved sealing machine adapted for sealing the waxed paper wrapping of sandwiches and like articles, which is effective for the purpose, simple and convenient to use, and compact in structure.

25 Further objects, and objects relating to structural details, will definitely appear from the detailed description to follow.

I accomplish the objects of my invention by the devices and means described in the following specification. The invention is clearly defined and pointed out in the claims.

30 A structure which is a preferred embodiment of my invention is clearly illustrated in the accompanying drawings, forming a part of this specification, in which:

Figure I is a plan view of my improved sealing machine, a portion of the front end being broken away.

40 Fig. I^a is a plan view of the portion of my improved machine in front of line a—a of Fig. I.

Fig. II is a side elevation of the parts shown in Fig. I.

45 Fig. III is an inverted view thereof.

Fig. IV is a detail longitudinal section on a line corresponding to line 4—4 of Figs. I and III.

50 Fig. V is a transverse section on a line corresponding to line 5—5 of Figs. I and III.

Fig. VI is a detail transverse section through the heating plate and heating unit.

55 Fig. VII is a longitudinal section through the heating unit on a line corresponding to line 7—7 of Fig. VI.

Fig. VIII is a vertical transverse section

through the wrapping means on a line corresponding to line 8—8 of Fig. IX.

Fig. IX is a side elevation of the front end of the machine, the rear end being 60 broken away, one of the steps of wrapping an article being illustrated.

Fig. X is a detail side elevation showing another step of the wrapping.

Fig. XI is a detail side elevation showing 65 the article completely wrapped and passing to the heating plate.

In the drawing similar reference characters refer to similar parts throughout the several views, and the sectional views are 70 taken looking in the direction of the little arrows at the ends of the section lines.

Referring to the drawing, my improved sealing machine, as embodied, comprises the transverse base members 1 formed of bars 75 yoke-shaped to provide legs 2 terminating in feet 3 having holes 4 therein adapted to receive screws so that the machine may be attached to a table or other support if desired.

80 Longitudinal base bars 5 are secured to the transverse base members by means of bolts 6. Uprights 7 having inwardly projecting arms 8 at their upper ends and inwardly projecting arms 9 at their lower ends are mounted 85 on the cross bars in opposed pairs, the lower arms 9 being arranged on the bars below the longitudinal bars 5 and secured by the bolts 6.

85 The heating plate 10 is formed of an inverted channel and is disposed between the uprights and secured thereto by bolts 11 arranged through the arms 12 of the heating plate,—see Fig. V. At the rear of the heating plate is a cooling plate 13, preferably 90 of wood. The surfaces of the heating and cooling plates are in the same plane so that the article to be sealed may be slid along on the heating plate and on the cooling plate.

95 A pair of side bars 14 are provided. These 100 side bars are supported by the short rods or studs 15 reciprocating through holes 16 in the uprights and held yieldingly inward by the coiled springs 17 arranged on the rods.

105 Cotters 18 arranged through holes 19 in the rods, there being a plurality of holes to provide for adjustment, limit the inward movement of the side bars. Top bars 20 supported by rods 21 reciprocating through holes 22 in the arms 8 of the uprights prevent lateral movement of the rods. Bearings 23 are mounted upon the arms. The

rods are provided with a series of holes 24 adapted to receive cotters 25 so that the inward movement of the rods may be regulated. The top bars are held yieldingly inward by coiled springs 26.

The heating unit, designated generally by the numeral 27, is adjustably mounted below the heating plate and retained by means of the threaded posts 28. This heating unit 10 comprises a pair of plates between which is the resistance wire 29 with proper insulation. As the details of the heating unit form no part of this invention they are not further described herein.

15 Binding posts 30 of the heating units project downwardly to receive the circuit wire 31.

The wrapping means comprises a wrapping way formed, in the structure illustrated, 20 of a pair of bars 32 having downwardly inclined front ends 33, —see Figs. I^A and IX. The horizontal portion of these bars is supported in substantially the plane of the sealing way formed in the structure illustrated by the heating plate 10. The front end of the sealing plate has a V-shaped recess with downwardly curved edges 34. The rear end of the wrapping way lies within the V-shaped recess of the sealing way 10, as best 25 shown in Figs. I^A and VIII. The rear ends of these way bars 32 are supported by posts 35 carried by brackets 36 adjustably mounted by means of the screw 37 engaging slots 38 in the brackets, the screw being carried 30 on the plate 39. This plate 39 is carried by the longitudinal bars 5.

A pair of brackets 40 carrying posts, (not 40 illustrated) similar to the posts 35, are mounted on the front end of the plate 39, being adjustably mounted by means of a screw 37, as described. The front ends of the way bars 32 are supported by the bars 41 mounted on the brackets and extend forwardly therefrom as shown in Fig. IX. The 45 brackets 36 and 40 have overhanging arms 36' and 40' with laterally turned ends 42 to which the folders 43 are secured. The folders are supported in a rearwardly inclined relation and have inwardly curved rear ends 44 disposed below and at the rear of the way bars 32, the outer corners 45 of which are curved to correspond to the curved ends of the folders 43. The front brackets 40 are higher than the rear brackets 36 so that the 50 front ends of the folders 43 are well above the wrapping way. The folders 43 are positioned so that the main portions thereof lie in planes slightly outside of the vertical planes of the outer edges of the wrapping 55 way so that when an article with a wrapper wrapped partially around the same is pushed along the way the projecting ends of the wrapper are engaged by the folders 43 and the folding completed as the article is pushed 60 onto the sealing way.

The machine designed is particularly adapted for the wrapping of articles, such as sandwiches, with waxed paper.

In operating the machine one very satisfactory method is to fold the wrapper over 70 the rear edge of the article and with a swinging movement bring the article onto the ways. This carries the free front end of the wrapper over the front edge of the article as shown in Fig. IX, and the article is pushed 75 along the wrapping ways bringing the ends of the wrapper into engagement with the folders 43 which carry it down across the ends of the wrapper and folds its edges under the same as the article passes over the 80 curved ends 44 and onto the sealing plate 10. As the article is pushed over the heating plate the wax of the different folds is fused 85 sufficiently to unite the folds and as the article is passed onto the cooling plate 13 from the heating plate the wrapping is held until the wax has set.

The machine is of large capacity and may be easily operated. It is especially designed by me for sealing the wrappers of sandwiches and the like for which purpose it is found to be very efficient. The machine is advantageous for use without the folding mechanism, the articles being completely wrapped before being fed into the machine. 95 The wrapping mechanism, however, is of decided advantage as the articles may be wrapped and sealed with great rapidity.

I have illustrated and described my improvements as I have embodied or adapted 100 the same for sealing sandwiches. I have not attempted to illustrate other embodiments or adaptations as I believe the disclosure made will enable those skilled in the art to which my invention relates to embody or 105 adapt the same as may be desired.

Having thus described my invention, what I claim as new and desire to secure by Letters Patent, is:

1. A sealing machine comprising spaced 110 transverse base members, a pair of longitudinal base bars, uprights having inwardly projecting arms at their upper and lower ends disposed in opposed coacting pairs with their lower arms upon said transverse base 115 members, said longitudinal bars being disposed upon such arms, the superimposed parts being secured together by bolts there-through, an inverted channel-shaped heating plate disposed between said uprights and 120 having its arms secured thereto, a heating element mounted on said longitudinal bars below said heating plate, a cooling plate disposed on said longitudinal bars at the rear of said heating plate, the surfaces of said 125 heating and cooling plates being in the same plane, yielding side bars supported by rods slidably arranged through said uprights and having springs thereon, said rods being provided with pins limiting their inward move- 130

ment, and yielding top bars supported on the upper arms of said uprights by rods reciprocating through said arms and having springs thereon, said rods being provided

5 with pins limiting their inward movement.

2. A sealing machine comprising spaced transverse base members, a pair of longitudinal base bars, uprights having inwardly projecting arms at their upper and lower ends disposed in opposed coacting pairs with their lower arms upon said transverse base members, said longitudinal bars being disposed upon such arms, the superimposed parts being secured together by bolts there-
10 through, an inverted channel-shaped heating plate disposed between said uprights and having its arms secured thereto, a heating element mounted on said longitudinal bars below said heating plate, a cooling plate disposed on said longitudinal bars at the rear of said heating plate, the surfaces of said heating and cooling plates being in the same plane, and side and top bars yield-
15 ingly mounted on said uprights and their upper arm, respectively.

3. In a sealing machine, the combination of spaced transverse base members, longitudinal base bars secured thereto, uprights having inwardly projecting arms at their upper ends mounted on said base in opposed coacting pairs, a heating plate disposed between said uprights, a heating element mounted below said heating plate, a cooling plate disposed at the rear of said heating plate, the surface of said heating and cooling plates being in the same plane, yielding side bars supported by rods slidably arranged through said uprights and having springs thereon, said rods being provided
20 with adjustable means limiting their inward movement, and yielding top bars supported on the upper arms of said uprights by rods reciprocating through said arms and having springs thereon, said rods being provided
25 with adjustable means limiting their inward movement.

4. In a sealing machine, the combination of a sealing way having at its front end a V-shaped recess with downwardly curved edges, yielding side and top bars supported in coacting relation to said sealing way, a wrapping way consisting of a pair of bars having downwardly inclined front ends disposed with their rear ends adjacent to but spaced from the front end of said sealing way, adjustable brackets on which said way bars are mounted, said brackets having overhanging arms at the sides of the wrapper way, and bar-like folders having inwardly curved rear ends mounted on said overhanging arms of said brackets in a rearwardly inclined position and so that their curved rear ends lie below the plane of the wrapping way bars and in proximity to the sealing way so that the projecting ends of a wrap-

per folded over an article are engaged and folded by the folders as the article is pushed along the wrapping way and onto the sealing way.

5. In a sealing machine, the combination 70 of a sealing way having at its front end a V-shaped recess with downwardly curved edges, a wrapping way consisting of a pair of bars having downwardly inclined front ends disposed with their rear ends adjacent 75 to but spaced from the front end of said sealing way, brackets on which said way bars are mounted, said brackets having overhanging arms at the sides of the wrapper way, and bar-like folders having inwardly 80 curved rear ends mounted on said overhanging arms of said brackets in a rearwardly inclined position and so that their curved rear ends lie below the plane of the wrapping way bars and in proximity to the sealing way so that the projecting ends of a wrapper folded over an article are engaged and folded by the folders as the article is pushed along the wrapping way and onto the sealing way. 90

6. In a sealing machine, the combination of a sealing way having at its front end a V-shaped recess with downwardly curved edges, a wrapping way disposed with its rear end adjacent to but spaced from the 95 front end of said sealing way, and rearwardly inclined folders having inwardly curved portions lying below the plane of the wrapping way and in proximity to the sealing way so that the projecting ends of a wrapper folded over an article are engaged and folded by the folders as the article is pushed along the wrapping way and onto the sealing way. 100

7. In a sealing machine, the combination 105 of a sealing way, a wrapping way disposed with its rear end adjacent to but spaced from the front end of said sealing way, and rearwardly inclined folders having inwardly curved portions lying below the plane of 110 the wrapping way and in proximity to the sealing way so that the projecting ends of a wrapper folded over an article are engaged and folded by the folders as the article is pushed along the wrapping way 115 and onto the sealing way.

8. The combination of a plate having at its front end a V-shaped recess with downwardly curved edges, a wrapping way consisting of a pair of bars disposed with their 120 rear ends adjacent to but spaced from the front end of said plate, brackets having overhanging arms at the sides of the wrapper ways on which said way bars are mounted, and bar-like folders having inwardly curved 125 rear ends mounted on said overhanging arms in a rearwardly inclined position with their curved rear ends below the rear end of the wrapping way and in proximity to said plate so that the projecting ends of a 130

- wrapper folded over an article are engaged and folded by the folders as the article is pushed along the wrapping way and onto the plate.
- 5 9. The combination of a wrapping way consisting of a pair of bars, brackets having overhanging arms at the sides of the wrapper ways on which said way bars are mounted, and bar-like folders having inwardly curved rear ends mounted on said overhanging arms in a rearwardly inclined position with their curved rear ends below the rear end of the wrapping way so that the projecting ends of a wrapper folded over an article are engaged and folded by the folders as the article is pushed along the wrapping way.
- 10 10. The combination of a plate having a downwardly curved front edge, a wrapping way disposed with its rear end adjacent to but spaced from the front end of said plate, and rearwardly inclined folders

having inwardly curved portions lying below the plane of the wrapping way and in proximity to said plate so that the projecting ends of a wrapper folded over an article are engaged and folded by the folders as the article is pushed along the wrapping way and onto the plate.

11. The combination of a way, and rearwardly inclined folders having inwardly curved portions lying below the plane of the way so that the projecting ends of a wrapper folded over an article are engaged and folded by the folders as the article is pushed along the way.

In witness whereof I have hereunto set my hand and seal in the presence of two witnesses.

WILLIAM E. MILLER. [L. S.]
